UNITED STATES PATENT OFFICE.

WILLIAM H. REYNOLDS, OF TOLEDO, OHIO, ASSIGNOR TO THE RANSOM & RANDOLPH COMPANY, OF TOLEDO, OHIO, A CORPORATION OF OHIO.

DENTAL STOOL OR THE LIKE.

No. 909,223.

Specification of Letters Patent.

Patented Jan. 12, 1909.

Application filed August 10, 1908. Serial No. 447,799.

To all whom it may concern:

Be it known that I, WILLIAM H. REYNOLDS, a citizen of the United States, and a resident of Toledo, in the county of Lucas and State of Ohio, have invented a certain new and useful Dental Stool or the Like; and I do hereby declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to vertically adjustable stools, chairs, or the like; and has for its object the provision, in an article of this class, of a simple and highly efficient friction clutch, which is adapted to permit a 20 free and unrestricted raising of the seat rod or shaft and to effectually lock the same in any desired position of vertical adjustment relative to the standard with which it telescopes, and which is capable 25 of being easily and quickly released to permit a lowering of the seat-rod by gravity.

The operation, construction and arrangement of the parts of the invention are fully described in the following specification, and 30 illustrated in the accompanying drawings, in which,—

Figure 1 is an elevation of a stool embodying my invention with the upper portion of the standard in section and the seat 35 partially raised, and Fig. 2 is a top plan view of the clutch parts with the standard head removed.

Referring to the drawings, 1 designates a stool base of any suitable construction 40 from which rises the hollow or tubular standard 2 having the head casting 3 at its upper end, as shown. Telescoping within the standard 2 and head for longitudinal adjustment therein is the seat-post 4, which has the seat 5 preferably swiveled 45 to its upper end in a suitable manner. The head casting 3, which is longitudinally bored to receive the seat-post or rod 4, has the upper end portion of such bore enlarged to receive the bushing 6, the inner 50 surface of which tapers inwardly from top to bottom thereof to provide an opening of frusto-conical shape, as shown. Mounted within the annular pocket formed between the bushing 6 and seat-post 4 are a plurality

of clutch balls 7, which are intended to coat with the tapered surface of the bushing and with registering grooves 8, provided longitudinally in the post surface, to frictionally resist a lowering of the seat-post from a position to which it has been elevated relative to the standard. The seating of the balls 7 is influenced by the action thereon of the spring-pressed collar 9, which loosely encircles the seat-post above 60 the balls. A coiled spring 10 yieldingly acts on said collar to hold the balls to their seat and has its outer end thrust against a plate 11, which is secured to the top of the head 65 3 to close the outer end of the enlarged portion of the bore therein.

Mounted within the lower or inner end of the enlarged portion of the head bore is the releasing collar or sleeve 12 which loosely encircles the rod 4 with its upper 70 end adapted to work freely within the lower contracted end of the bushing 6 to adapt the collar when raised to engage and lift the balls 7 from their seat against the tension of the spring 10, to permit a lowering 75 of the post 4 and its seat. The collar or sleeve 12 normally seats by gravity upon the bottom of the enlarged portion of the head bore with its upper end free from contact with the balls, and has its lower end formed 80 with the radial flange 13, which permits a limited longitudinal movement of the collar relative to the bushing, due to the spacing of the lower end of the bushing from the bottom of the bore by shouldering it therein 85 90 or otherwise.

Mounted at the lower portion of the standard is a treadle 14, which has one end projected within the standard 2 and attached to the lower end of a trip-rod 15, 95 which is disposed within the standard at one side of the seat-post 4. The trip-rod 15 has its upper end working through a suitable bore provided in the head-casting at the side of the seat-post and coacts at 100 such end with the under side of the collar or sleeve 12, whereby a raising of the trip-rod by a lowering of the outer end of the treadle effects a raising or releasing movement of the collar or sleeve 12. 105

It is thus apparent that in the use of a stool or chair equipped with my clutch mechanism the seat-rod 4 may be freely raised to any desired position of adjustment relative to the standard, but cannot be low- 110

ered, except when the treadle 14 is tripped, due to the clutch-balls 7 instantly coöperating with the bushing 6 to lock the seat-post against such movement as soon as the 5 raising movement thereof ceases. To lower the seat it is only necessary to depress the treadle 14, which effects a raising of the collar or sleeve 12, through the medium of the trip-rod 15, to engage and unseat the clutch 10 balls, the depression of the treadle being maintained until the seat has lowered by gravity to the desired position.

I wish it understood that I do not desire to be restricted to the exact details of construction and arrangement of the parts 15 shown and described, as obvious modifications will occur to persons skilled in the art.

Having thus described my invention, what I claim as new and desire to secure by Letters Patent, is,—

1. In combination, a standard, a seat-post telescoping within the same for relative longitudinal adjustment, a member carried by the standard and encircling the post, said 25 member having an inner tapered surface, clutch-balls coöperating with said member to lock the post against a lowering movement, means yieldingly acting on the balls to hold them in seated position, a collar 30 loosely encircling the post at the lower end of said member and adapted to work upwardly therein to engage and unseat the balls to permit a lowering of the post, and manually controlled trip-means for effecting 35 an upward movement of the collar.

2. In combination, a hollow standard, a head carried by the standard and having a bore therethrough which is enlarged at its outer end, a seat-post working through said 40 bore and within the standard, a bushing disposed within the enlarged portion of the head bore and having a frusto-conical interior, balls coöperating with the interior of

the bushing to prevent a lowering of the seat-post relative to the head, means yieldingly acting on the balls to normally maintain them seated, a sleeve loosely encircling the post at the base of the enlarged portion of the head bore and having its upper end working within the bushing, and manually 50 controlled means for raising the sleeve relative to the bushing to engage and unseat the balls, substantially as described.

3. In combination, a hollow standard having its head provided with a seat-post opening which is enlarged at its outer end, a seat-post mounted for longitudinal adjustment in said opening and having longitudinal grooves in its surface, a plate closing the outer end of the opening around the 55 post, a bushing secured in the enlarged end of said opening above its base and having a frusto-conical opening therethrough, clutch-balls mounted within the annular opening between the bushing and post and seating 60 in the post grooves to prevent a lowering of the post relative to the head, a ring resting on the balls, a compression spring acting in opposition on said plate and ring to influence a seating of the balls, a sleeve mounted 65 in the base of the enlarged portion of the head opening for limited longitudinal movement therein, said sleeve encircling the post and having its upper end working within the bushing to adapt a raising of the sleeve 70 to engage and unseat the balls, a treadle carried by the standard, and a trip-rod within the standard and movable by the treadle to raise the sleeve.

In testimony whereof I have hereunto 80 signed my name to this specification in the presence of two subscribing witnesses.

WILLIAM H. REYNOLDS.
